(57) **CLAIM**

The ornamental design for a decorative light, as shown and described.

DESCRIPTION

FIG. 1 is a perspective view of a decorative light showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is a perspective view of the decorative light shown in a position of use with environmental subject matter; and, FIG. 9 is an enlarged view, of circled portion 9, of FIG. 8, thereof.

The broken lines throughout the drawing figures depict portions of the decorative light that form no part of the claimed design.

The dot-dash broken lines depict the boundaries of the FIG. 8 and FIG. 9 enlargement that form no part of the claimed design.
